[37] CLAIM

The ornamental design for a carton, as shown.

DESCRIPTION

FIG. 1 is a front elevational view of a carton showing my new design;

FIG. 2 is a side elevational view looking from the right of FIG. 1 with the bottom easel in an extended position; FIG. 3 is a rear elevational view;

FIG. 4 is a side elevational view showing the side opposite that seen in FIG. 2;

FIG. 5 is a top plan view;

FIG. 6 is a bottom plan view; and

FIG. 7 is a side elevational view similar to FIG. 4 but showing the bottom easel folded into the carton.

FIG. 1

FIG. 2

FIG. 3

FIG. 7

FIG. 4
